LANTERN.

1,139,788.

Specification of Letters Patent.

Patented May 18, 1915.

Application filed January 22, 1915. Serial No. 3,817.

To all whom it may concern:

Be it known that we, EDWARD J. McDADE and FARNUM F. DORSEY, citizens of the United States, and residents of Rochester, in the county of Monroe and State of New York, have invented certain new and useful Improvements in Lanterns, of which the following is a specification.

This invention relates to lanterns of the type commonly described as "railroad lanterns," in which the currents of air and of the products of combustion through the globe are controlled by passages in the body and in the head or dome of the lantern, 15 without the employment of air-tubes for equalizing the air-pressure at the top and bottom of the lantern. In lanterns of the type in question considerable difficulty has been encountered in properly controlling the 20 air-currents within the globe in such manner as to insure a sufficient supply of air for proper combustion, while at the same time avoiding the danger of drafts such as may extinguish the flame under the exacting 25 conditions of use. To control the indraft of air at the bottom of the globe it has been customary to mount the removable oil-font of the lantern in a hollow body-portion in the form of a shell or ring, this body being, 30 for at least a part of its height, of sufficiently greater diameter than the oil-font to provide an annular air-space, and being perforated for the admission of air to this space. From the air-space in question the 35 air has been delivered at, or adjacent to, the top of the oil-font through openings or passages of various forms more or less adapted to control and direct the air-currents. In lanterns of the type in question 40 it is customary to employ a globe of which the lower edge rests upon a horizontal flat seat or ledge at or near the top of the lantern-body, this globe-seat extending into proximity with the top of the oil-font. It 45 has been proposed, as in the United States patent to Hamm, No. 910,673, to employ the globe-seat as means for regulating the inflow of air at the top of the oil-font, this result being accomplished by extending the 50 globe-seat into engagement with the oil-font and providing the globe-seat, at its inner margin with perforations for the passage of the air. This arrangement, however, causes the air-currents flowing through the 55 perforations in question to be directed up-

wardly into the globe, instead of causing them to flow in the direction of the burner where the air is required for the maintenance of combustion. It has also been proposed, as in the patent to Herman, No. 910,681, to provide for the inflow of air at the top of the oil-font by arranging the oil-font with its top a short distance below the globe-seat, so that an annular space is provided between the upper angle or edge of the oil-font and the inner edge of the globe-seat, but in this case the air-currents, while directed in a generally horizontal direction toward the burner, are not equally distributed around the burner, but may prevail in one direction or the other according as the air is admitted in greater volume at one side or the other of the body owing to wind or to the lateral movement of the lantern in signaling.

The object of the present invention is to produce a lantern in which the inflow of air at the top of the oil-font shall be such that the air is directed in the general direction of the flame of the lantern, but in which the flow of air is equally distributed around the oil-font, so that the flame is subjected to no pronounced lateral draft in any direction. For the foregoing purpose we locate the globe-seat at a substantial distance above the top of the oil-font, and provide a sleeve extending downwardly from the inner edge of the globe-seat and to a point below the top of the oil-font. This sleeve is provided with a series of perforations adjacent to the top of the oil-font, these perforations being sufficient in number and size to admit the necessary quantity of air, while at the same time the sleeve affords sufficient obstruction to the flow of air to cause this flow to be distributed substantially uniformly around the oil-font, so that under all conditions the air approaches the flame of the lantern substantially uniformly from all directions. Preferably, the diameter of the sleeve in question is somewhat greater than that of the oil-font, while its lower margin is contracted so as to engage the oil-font and substantially close the space between the sleeve and the oil-font against the direct upward flow of air along the sides of the oil-font, and it has also been found desirable to locate the perforations in the sleeve partly above and partly below the upper edge of the oil-font, as this arrangement causes the

air-currents passing through these openings to be broken up so as to result in a gentle and diffused current of air toward the flame of the lantern.

5 The accompanying drawing is a vertical sectional view of the lower part of a lantern embodying the present invention.

The invention is illustrated as embodied in a lantern of a well-known general form, 10 this lantern comprising the usual sheet-metal body 1 fixed in a wire frame or guard 2. The oil-font 3 is of ordinary form, and is provided with the usual open burner 4, such as is adapted for use with the heavier 15 illuminating oils. The lower part 5 of the body is contracted to fit the oil-font closely and retain the oil font against lateral movement, while the upper part of the body is of substantially greater diameter than the oil- 20 font so as to provide an annular air-space 6. Ingress of air to this space is permitted by the usual perforations 7 in the wall of the body.

The globe-seat is embodied in an annular 25 member of drawn sheet-metal, having a vertical portion 9 fitting closely within, and secured to, the upper margin of the body, and a flat inwardly-extending horizontal portion 8 which provides a surface upon 30 which the lower edge of the globe rests in the usual manner.

The novel features of the present construction reside particularly in a sheet-metal sleeve 10 which projects downwardly from the inner edge of the globe-seat. This sleeve 35 may be formed, and may be attached to the globe-seat, in any convenient manner, but it is preferably produced from the same blank and by the same stamping or drawing operation by which the globe-seat is produced, being thus an integral extension from the inner edge thereof. The sleeve 10, as shown, 40 extends for a short distance below the top of the oil-font, and is provided, at the bottom, with a contracted or inwardly-projecting flange 11 which extends substantially into engagement with the oil-font. A row 45 of perforations 12 is formed in the sleeve, these perforations being partly above and partly below the upper edge of the oil-font.

The flange 11 prevents air-currents from blowing directly along the surface of the oil-font into the space above the oil-font, so that the air admitted to the air-space 6 55 through the opening 7 emerges into the lantern-globe through the holes 12 and in the general direction of the burner 4. The im-

pingement of a part of this air against the edge of the oil-font, however, causes the air-currents to be more or less broken up and 60 checked, while at the same time the obstruction of the space between the globe-seat and the oil-font by the sleeve 10 prevents the free flow of any pronounced lateral draft in the direction of the burner. Accordingly, 65 the burner is supplied with air from all directions equally in such a manner that the flame will burn very steadily under the most adverse conditions.

We claim:—

1. In a lantern, the combination, with an oil-font and a body in which the oil-font is removably mounted, the body being of substantially greater diameter than the oil-font so as to provide an annular air-chamber, 75 and having openings for the admission of air to said chamber, and a flat imperforate ledge, constituting a globe-seat, partly closing the top of the body and located above the top of the oil-font; of a sleeve extending downwardly, from the inner margin of the globe-seat, and close to the sides of the oil-font and provided with a series of perforations, located partly above and partly below the upper extremity of the oil-font, 85 for the admission of air from said air-chamber to the space above the oil-font.

2. In a lantern, the combination, with an oil-font and a body in which the oil-font is removably mounted, the body being of substantially greater diameter than the oil-font so as to provide an annular air-chamber, 90 and having openings for the admission of air to said chamber, and a flat imperforate ledge, constituting a globe-seat, partly closing the top of the body and located above the top of the oil-font; of a sleeve, of substantially greater diameter than the oil-font, extending downwardly from the inner margin of the globe-seat, to a point below 95 the top of the oil-font, and thence inwardly into close proximity to the oil-font, said sleeve having a series of perforations, opening above the top of the oil-font, for the admission of air from said air-chamber to 100 the space above the oil-font.

In testimony whereof we affix our signatures in presence of two witnesses.
